UNITED STATES PATENT OFFICE

130,339

DESIGN FOR A FLUORESCENT BED LAMP

Bernard A. Mitchell, Chicago, Ill.

Application September 26, 1941, Serial No. 103,528

Term of patent 7 years

To all whom it may concern:

Be it known that I, Bernard A. Mitchell, a citizen of the United States, residing at Chicago, in the county of Cook and State of Illinois, have invented a new, original, and ornamental Design for a Fluorescent Bed Lamp, of which the following is a specification, reference being had to the accompanying drawing, forming part thereof.

Fig. 1 is a perspective view of a fluorescent bed lamp showing my new design.

Fig. 2 is a top plan view of same.

Fig. 3 is a front elevational view of same.

Fig. 4 is an end elevational view of same.

I claim:

The ornamental design for a fluorescent bed lamp, as shown.

BERNARD A. MITCHELL.
